United States Patent Office.

JOHN GIBSON, JR., OF ALBANY, NEW YORK.

Letters Patent No. 60,714, dated January 1, 1867.

STREET-CAR HEATER.

The Schedule referred to in these Letters Patent and making part of the same.

TO ALL WHOM IT MAY CONCERN:

Be it known that I, JOHN GIBSON, Jr., of Albany, in the county of Albany, and State of New York, have invented a new and improved Street-Car Heater; and I do hereby declare that the following is a full, clear, and exact description thereof, which will enable others skilled in the art to make and use the same, reference being had to the accompanying drawings, forming part of this specification, in which—

Figure 1 is a central longitudinal section of a street car, showing the heating apparatus.

Figure 2 is an inverted view of a horizontal section, through the fire-grate.

Figures 3 and 4 are detached views of the draught doors and dampers, with pinch-screws connected.

Similar letters of reference indicate like parts.

The object of this invention is to warm street cars, which is accomplished by placing one or more stoves under the seat of a car, entirely out of the way of the feet of passengers, and conveying the smoke under the flooring and up to the roof, where it escapes without giving any annoyance, after radiating its heat into the car in its passage through the pipe. It is a simple and economical arrangement, and is so constructed that it may be detached and laid aside in warm weather. The fuel, which may be coal or wood, is introduced at the terminus station of a line of street cars, and the ashes discharged under the car, in nowise interfering with the passengers. The draught doors and damper in the pipe are held in place firmly, when set at any desired position, by means of pinch-screws, unaffected by the jolting or vibration of the car.

A represents an inside view of a street car, mounted on the wheels B B. A stove, C, of any suitable form and material, either cast or sheet iron, is fitted under the seat of the car, the grate *a* being placed beneath or near the flooring, over an ash-pan, *b*, which is arranged so that the ashes may be cleaned out or dumped outside of the car. The ash-pan *b* is provided with one or more sliding draughts or doors, *m m*, which are secured by a pinch or set-screw, *p*, or other device, to prevent displacement from the jolting or vibration of the car, as shown in figs 3 and 4. The stove may be constructed to have the fuel put in through a trap-door, *c*, in the seat *d d*, as represented, or on the outside of the car, if desired. The stove-pipe *e e* passes under the seat, from the stove to one corner of the car, and thence up through the roof; or it may be made to pass below the flooring, to and under the opposite seat, before rising to the roof. The pipe *e* is also to be properly protected with a guard-screen or perforated shield, *f*, and is also provided with a damper, *n*, held by a pinch-screw, *p*, or other device, to keep it in a fixed position, unaffected by the vibration of the car, as shown in figs. 3 and 4. A double sheathing or perforated screen, *D*, is placed under the seat in front of the stove, and may also be placed over it, to protect the passengers from an excess of heat by the direct radiation against their persons.

Having described the construction and application of my invention, what I claim as new, and desire to secure by Letters Patent, is—

1. The stove C, arranged within the space between the seat and the bottom of the car, A, and provided with the ash-box *b* beneath it, substantially as herein set forth.
2. The perforated protecting plate D, on the front side of the seat, at the point where the stove is placed, substantially as and for the purpose specified.
3. The combination of the ash-pan *b*, draught doors *m m*, and pinch-screw *p*, when arranged as herein shown and described and for the purpose specified.
